US00D328562S

United States Patent [19]

Lin

[11] Patent Number: Des. 328,562

[45] Date of Patent: ** Aug. 11, 1992

[54] ROPE FASTENER

[76] Inventor: Yuan-Mao Lin, 3F, No. 73, Chih
Yuan Sec. 2 Rd., Shih Pai District,
Taipei, Taiwan

[**] Term: 14 Years

[21] Appl. No.: 616,301

[22] Filed: Nov. 20, 1990

[52] U.S. Cl. D8/373; D8/367

[58] Field of Search D8/385, 396, 367, 383;
248/62, 231.91, 241 P, 165; 24/115 KX;
D6/513
